MIXED PHENOXYPHENYL-ALKYL KETONES

Anderson W. Ralston and Carl W. Christensen,
Chicago, Ill., assignors to Armour and Company, Chicago, Ill., a corporation of Illinois

No Drawing. Application April 23, 1935,
Serial No. 17,873

5 Claims. (Cl. 260—131)

This invention relates to aralkyl ketones and it comprises, as new compounds, ketones having the generic structure

wherein R is a phenoxyphenyl radical and R' is an alkyl radical having five or more carbon atoms.

10 The higher fatty acids, and by that we mean those fatty acids derived from vegetable and animal oils and fats are extremely abundant materials and can be obtained at little expense. They have never, however, been used to any great extent as raw materials for the synthesis of more valuable substances. These fatty acids have been used almost exclusively in the soap industry, for making candles, etc., and in but relatively few instances have they been used as raw materials in what might be termed the "fine" organic chemical field.

We have now discovered a new class of compounds which can be made from the higher fatty acids and which have chemical and physical properties of marked technical and commercial interest. We have discovered that the higher fatty acid chlorides, such as stearyl chloride, myristyl chloride, lauryl chloride, caproyl chloride, and other acid chlorides derived from, and corresponding to the higher fatty acids, can be made to react with diphenyl ether, or substituted diphenyl ethers, to give aralkyl ketones having valuable properties which suit them for use in many technical applications. These aralkyl ketones are waxy solids and can be crystallized from organic solvents such as benzene, alcohol and others, to give pure ketones. The crystalline products, when melted and allowed to cool, yield substances of clearly defined "waxy" character, appearance and "feel". We have discovered that they are excellent dielectrics and can be used in electrical insulation. We have also discovered that these new substances are desirable constituents in waxing and polishing compounds. When added to lubricating oils, the ketones of the present invention confer beneficial properties on the oil.

In its broad aspects, our invention comprises new products having the generic formula

wherein R is a phenoxyphenyl radical which may be substituted or not and R' is an alkyl radical containing the alkyl residue of a higher fatty

acid. Thus, as an example, one of the new products falling within the scope of our invention is phenoxyphenyl heptadecyl ketone, which can be written structurally as follows:

In this case the $\text{C}_{17}\text{H}_{35}$, or heptadecyl radical, is the alkyl residue of stearic acid, $\text{C}_{17}\text{H}_{35}\text{COOH}$. This particular ketone has a melting point of 10 68° C.

Other typical ketones falling within the scope of our invention are:

phenoxypyhenyl tridecyl ketone
(melting point 53.5–54.5° C.)

15

phenoxypyhenyl undecyl ketone
(melting point 45–46° C.)

20

p-nitro phenoxypyhenyl heptadecyl ketone
(melting point 177–179° C.)

25

p-methyl phenoxypyhenyl heptadecyl ketone
(melting point 77–78° C.)

30

All of the products of the present invention can be made by the Friedel-Crafts or the Grignard synthesis.

Thus, for example, when we wish to make phenoxypyhenyl tridecyl ketone, we start with diphenyl ether and myristyl chloride. The myristyl chloride can be made in any of the known ways from myristic acid. Generally the myristic acid is reacted with phosphorous pentachloride or other chlorinating agent commonly used for converting aliphatic carboxylic acids to their corresponding acid chlorides. We then prepare a mixture containing about 14 parts by weight of diphenyl ether, 20 parts by weight of myristyl chloride and about 50 parts by weight of carbon disulphide. This mixture is cooled in an ice bath and about 22 parts by weight of aluminum chloride (dry) are slowly added with stirring until there is no further evolution of hydrochloric acid. The reaction mixture is then poured into

35

40

45

50

55

5 a mixture of ice and dilute hydrochloric acid to hydrolyze the complex aluminum compound formed in the reaction. Finally the resulting acid mixture is placed in a flask and subjected to steam distillation. This removes any excess 10 diphenyl ether and carbon disulphide from the reaction products. During the steam distillation, the phenoxyphenyl tridecyl ketone separates from the aqueous reaction mixture in the distilling flask as an oily supernatant liquid. It does not distil over with the carbon disulphide and can be separated from the aqueous solution of 15 aluminum chloride in the distilling flask by simple decantation. It is then taken up in acetone or other organic solvent and crystallized therefrom. Yields are high, generally better than 90% of theory.

20 In a similar manner we can start with substituted diphenyl ethers such as the methyl and nitro derivatives indicated above. Likewise, as stated, we can start with any acid chloride of the higher fatty acids. Generally we start with the acid chlorides of fatty acids having twelve or more carbon atoms since these fatty acids are 25 readily available and cheap. Our invention is therefore not limited to the specific compounds described above, since we are the first to de-

scribe aralkyl ketones, or mixed ketones, in which the aryl group is a phenoxyphenyl radical and the alkyl group is the alkyl residue of a higher fatty acid. And by higher fatty acid we mean those acids having six or more carbon atoms. 5

Having thus described our invention what we claim is:

1. Aralkyl ketones having the structural formula

10

wherein R is a phenoxyphenyl radical and R' is an alkyl radical having at least five carbon atoms.

2. Aralkyl ketones having the structural formula

15

wherein R is a phenoxyphenyl radical and R' is an alkyl radical having at least eleven carbon atoms. 20

3. A phenoxyphenyl heptadecyl ketone.

4. A phenoxyphenyl tridecyl ketone.

5. A phenoxyphenyl undecyl ketone.
